UNITED STATES PATENT OFFICE.

FRED N. LIVINGSTON, OF SEATTLE, WASHINGTON.

AUTOMOBILE-STARTER.

Specification of Letters Patent. Patented Sept. 21, 1915.

1,154,520.

Application filed June 8, 1914. Serial No. 343,806.

To all whom it may concern:

Be it known that I, FRED N. LIVINGSTON, a citizen of the United States, residing at Seattle, in the county of King and State 5 of Washington, have invented certain new and useful Improvements in Automobile Starters; and I do hereby declare the following to be a full, clear, and exact description of the invention, such as will enable 10 others skilled in the art to which it appertains to make and use the same.

This invention relates to improvements in starting apparatus for automobile motors.

Various expedients have been devised for 15 the starting of the motors of automobiles, but in the majority of instances these starting devices have proved ineffective for the purposes for which they have been designed. In the producing of these starting devices, 20 many of the same have been in the form of attachments more or less complicated in their nature, and because of the number of parts involved in their construction, and, in some instances, the use of springs, they have 25 involved considerable expense for their manufacture and application to selfpropelling vehicles.

The present invention has in view the provision of means for starting the motors of 30 automobiles by the initial application of a charge of the gaseous mixture employed for the operation of the motor in its normal running condition, thus dispensing with the employment of devices separate and distinct 35 from the motor itself, and enabling the motor to be started from the seat of the machine without the necessity of the operator thereof leaving the seat.

A further object of the invention is to provide 40 apparatus of the character referred to by means of which a starting charge of the gaseous mixture may be introduced to a pair of the cylinders of a motor, when the latter is of four or more cylinders, without, however, such a charge being fired until such is desired by the operator of the machine, means being provided to interrupt the circuit connections of the electrical ignition system prior to the time of the injection of 45 the charge into the cylinders, thereby guarding against accident, and at the same time conserving the initial explosive charge until 50

the proper quantity thereof has been admitted.

A further object of the present invention 55 is the provision of firing apparatus of the character stated, the construction of which is such that the initial explosive charges may be introduced to the cylinders in the proper quantity, and then fired by the manipulation 60 of but a single lever, this construction presenting the advantage of reducing the controlling part to a minimum, and adding but slightly to the controlling devices now positioned upon and adjacent to the seat of the 65 machine operator.

Other objects and advantages of the improvements will appear as the nature of the invention is better understood, the invention consisting substantially in the novel construction, combination and arrangement of parts, hereinafter fully described, illustrated 70 in the accompanying drawings and pointed out in the appended claims.

In the drawings: Figure 1 is a top plan 75 view of an explosive automobile motor equipped with the herein-described invention. Fig. 2 is a side elevation thereof. Fig. 3 is a vertical longitudinal sectional view, illustrating the positions of the auxiliary 80 valves at different stages of the operation of the motor. Fig. 4 is an elevation of the timer and the igniting device associated therewith for exploding the starting charge. Fig. 5 is a plan view of the construction 85 illustrated in Fig. 4, the casing being illustrated in open position. Fig. 6 is a transverse sectional view of the construction illustrated in Figs. 4 and 5, the case being closed. Fig. 7 is a detail plan view of the cut-out 90 and the associated parts. Fig. 8 is a detail elevation of one of the cam sleeves employed for actuating the auxiliary valves and illustrating the relation thereof to the valve rods of the cylinders. Fig. 9 is a similar view 95 taken at right angles to the view point of Fig. 8, the actuating rod for the cam sleeves being shown in section.

Referring in detail to the accompanying drawings, the numerals 1, 2, 3 and 4 illustrate the cylinders of a conventional automobile motor. The cylinders are mounted upon the common frame 5 and are provided with the usual inlet valves 6 and outlet

valves 7, typical of automobile motors, said valves being operated by the conventional levers 8 and 9. The cylinders, moreover, are provided also with the usual intake 10 leading from a manifold 11, which latter is connected to a carbureter 12 in the usual way. The exhaust valves 7 discharge into the usual exhaust pipe 13. These parts are merely referred to for clearness of understanding of the relation of the present invention to the conventional motor.

As before stated, the present invention contemplates the provision of means for introducing a starting charge of fuel to the cylinders of the motor, the particular cylinders, however, into which the charge is injected being controlled by the position of the auxiliary valves to be hereinafter described. To the accomplishment of this end a pump 14 is associated with the motor, and is connected to the carbureter 12 by means of a pipe 15, in which is arranged a check valve 16. The pump 14 may be of any usual construction, but is preferably of the type in which a reciprocating plunger or piston is arranged, said piston being operated by means of a crank 17 having engagement with the piston rod of the pump by means of a connecting link 18. The pump 14 is provided also with a discharge pipe 19 having a check valve 20 arranged therein, and said pipe 19 is connected to a manifold 21 from which lead a plurality of feed pipes 22.

Each of the feed pipes 22 is connected to one of the cylinders of the motor, communication between each cylinder and its feed pipe 22 being controlled by an auxiliary valve 23. Each of the valves 23 is actuated by a rock lever 24, said lever being operated by means of auxiliary valve rods 25, which rods are slidably mounted in guide lugs 26 arranged at the exterior of the cylinders. Interposed between one of said lugs 26 and a collar 27 on each of the rods 25 is a coil spring 28 by means of which the respective valves are held to their seats.

The crank 17 is arranged at one end of an operating shaft 29, which shaft extends transversely of the frame of the motor, and at the end of said shaft opposite to that which the crank 17 is connected is arranged a hand lever 30. This hand lever extends through a guide frame 31, at the outer side of which is formed a notch 32 in which the lever 30 is normally seated, and thus locked against movement until pressure is applied thereto. For holding the lever 30 in the notch 32 a coil spring 33 is connected to said lever and to a suitable post 34 on the guide 31, which spring exerts its tension normally to draw the lever 30 into the notch 32. At the opposite side of the guide 31 is a notch 35 into which the lever 30 may be forced against the tension of said spring 33, and

when so introduced such lever is positioned for igniting the starting charge as will be presently explained.

The inlet valves 6 and outlet valves 7 are operated by means of the usual valve rods 36 and 37, respectively, said rods being given reciprocation by means of cams 38 and 39 carried by a cam shaft 40 connected by gears 41 to the crank shaft 42 of the engine, in the usual manner. The valve rods 25, however, of the auxiliary valves 23 are actuated by means of a slide rod 43, said rod carrying a plurality of cam sleeves 44, one of which is provided for each of the motor cylinders. These cam sleeves are more clearly illustrated in Figs. 8 and 9, and by referring to these views it will be noted that each of the cam sleeves 44 is slidably mounted in relation to the rod 43 through the medium of pins 45 carried by the rod 43 and passing through slots 46 in the sleeve. Coil springs 47 are associated with the cam sleeve 44, said springs bearing against one of the pins 45 and the opposite end of the slot 46 in which the pin is seated, and by means of said springs 47 a yielding connection is afforded between the cam sleeve and the rod 43. Hence if the sleeves 44 are unobstructed in their movement they will be actuated simultaneously with the rod 43, but if they be checked in their movement, under conditions as will presently appear, said sleeves remain stationary while the rod 43 may readily slide, the springs 47 of the cam sleeves which are locked against movement being compressed under the movement of the rod 43 at this time.

Each of the sleeves 44 is provided at one end with a cam lug 48, said lugs being arranged at the upper sides of said sleeves, and at the opposite sides of the latter they are provided with spaced shoulders 49 designed to engage locking lugs 50, one of which is carried by each of the valve rods 36 and 37. When the valve rods 36 and 37 are moved upwardly to a sufficient extent by their respective cams 38 and 39, the locking lugs 50 are projected into the path of the shoulders 49, and when so positioned the shoulders 49, on the forward movement of the rod 43, will engage said locking lugs, which lugs will prevent forward movement of the cam sleeve 44 under these conditions. Hence, the cam lugs 48 are locked against movement beneath the auxiliary valve rods 25, so that these valve rods remain inactive, their respective valves 23 remaining closed. It will be understood, however, that the movement of the auxiliary valves 23 is properly timed so that certain of these valves will be open while the others are closed, and in the cycle of movements incident to the operation of the motor, the auxiliary valves 23 of the respective cylinders will be opened at proper times to permit the

injection of a starting charge whenever such shall be required for initiating movement of the motor. It will be further understood that the rod 43 is controlled manually, and 5 during the operation of the motor under normal conditions this rod remains perfectly stationary. Accordingly, the respective cam sleeves 44 and the auxiliary valves 23 are stationary, and said valves are closed. 10 Therefore, as the explosive charges are admitted to the respective cylinders these charges do not escape through the auxiliary valves 23, but are confined in the cylinders and successively ignited in the cycle of 15 movements incident to the working of the motor.

To impart the requisite movement to the rod 43 in a forward direction said rod is connected to a bell-crank lever 51 pivoted 20 to the frame of the motor at the rear end thereof, a pin-and-slot connection 52 being employed between the bell-crank lever 51 and the rod 43, and the free end of said lever 51 co-operated with a cam 53 which is carried by the operating shaft 29. When the operating shaft 29 is actuated for the operation 25 of the pump 14, the cam 53 swings the bell-crank lever 51 upon its fulcrum and in this movement the rod 43 is projected forwardly. This operation occurs when the handle 30 is moved in a rearward direction 30 in the guide 31, or pulled toward the operator of the machine as the operator is seated therein. When, however, the handle 30 is moved forwardly and the cam 53 resumes its 35 normal position, a spring 54, which is arranged at the forward end of the rod 43, and is interposed between a stationary lug 55 on the motor frame and a collar 56 carried by the rod 43, forces said rod 43 in a rearward direction, the spring 54 becoming compressed when the rod 43 is projected forwardly. Thus, the rod 43 is automatically 40 returned to a position which removes the cam lugs 48 from beneath the auxiliary valve rods 25 on the rearward movement of the rod 43, and those auxiliary valves 23 which have been opened become closed.

The mechanism thus far described provides 45 means for permitting the starting charges to be introduced to the respective cylinders of the motor. After being so introduced, it is necessary, of course, that the charges shall be properly and timely exploded, and to provide for this mechanism now to be described is employed. In this connection it may be noted that the present invention contemplates the use of igniting means which is associated with the timer 50 of the motor, and referring to Figs. 4, 5 and 6 this ignition means will be clearly understood. In the views in question, the numeral 57 designates a contact finger which is mounted upon a rotary shaft 58 to which 55 is connected a miter gear 59, said miter gear

meshing with a similar gear 60 that is carried by the cam shaft 40. The contact finger 57 is designed to wipe over a plurality of stationary contacts 61 carried by the base section 62 of a timer casing, to which base 70 section is hingedly connected a cover section 63. The stationary contacts 61 are electrically connected in the ignition system in the usual way, but as this forms no part of the present invention, it is unnecessary to 75 describe the same.

In the cover section 63 is mounted a movable support 64, and said support carries a plurality of stationary contacts 65 which are arranged in such manner as to overlap the 80 spaces between the contacts 61 of the base member 62. The arrangement of the contacts 61 will be recognized as an arrangement commonly practised in the art, and as the circuit is made by the contact finger 57 85 contacting with the respective contacts 61, it will be readily understood that a spark is produced in the respective cylinders of the motor in the usual way, (as by an induction coil not shown). The purpose of arranging 90 the contacts 65 so that they extend over the spaces between the contacts 61, when the cover section 63 is closed upon the base section 62, is to permit a spark to be produced in the several cylinders of the motor at any 95 position of the pistons therein. Normally, however, the contacts 65 have no engagement with the contact finger 57 but are held away from said finger by means of a coil spring 100 66 which surrounds a post 67 that projects at the exterior of the cover section 63, the spring 66 being interposed between said section 63 and a collar 68 carried by the post 67. Therefore, the spring 66 urges the post 105 67 outwardly, but when pressure is applied to said post, in opposition to the tension of the spring 66, the contacts 65 may be brought into such relation with the finger 57 that, regardless of the position of the finger 57 in its path of rotation, an electrical circuit 110 will always be closed and a spark continually generated in the motor, as long as post 67 is depressed.

For the purpose of actuating the post 67 in the manner which has just been described 115 an operating rod 69 is employed, the forward end of said rod being provided with a deflected foot 70 which engages the post 67. The rear end of said rod 69 is connected to a bell-crank lever 71, fulcrumed upon the motor frame and having its free end pivotally connected to a slide rod 72, the latter extending transversely of the motor frame, and being urged in one direction by means of a coil spring 73 interposed between a supporting bracket arm 74 wherein the rod 72 is slidably mounted and a collar 75 carried by the rod 72. The normal tendency of the spring 73 is to retract the rod 69 so that the deflected foot 70 will permit the spring 66 120 125 130

to expand, and thus remove the contacts 65 from engagement with the contact finger 57. The rod 72, however, is designed to be moved in opposition to the movement induced by the spring 73 by the manual operation of the hand lever 30, to which end said lever 30, when the latter is opposite to the rod 72 and thereby in a position to engage the same, may be moved into the notch 35, and in this movement the rod 72 is caused to swing the bell-crank lever 71 upon its fulcrum and thereby project the operating rod 69 in a forward direction. In this movement of the rod 69 the deflected foot 70 wipes over the post 67, forcing the latter inwardly against the pressure of the spring 66 and thereby positioning the contacts 65 in engagement with the finger 57. Upon pressure being released from the hand lever 30 said lever is returned to the notch 32 by the spring 33 and pressure being released from the rod 72, the spring 73 reasserts itself, and in this movement retracts the operating rod 69, whereupon pressure being relieved from the post 67, the spring 66 forces said post outwardly and again frees the contacts 65 from engagement with the finger 57.

It frequently occurs in the operation of automobile motors that when the same comes to rest the contact finger of the timer remains upon one of the stationary contacts with which it co-operates for producing a spark. Manifestly, under these conditions, the injection of a starting charge of fuel into the cylinder the contact of which is in engagement with the finger 57 would cause a premature ignition of such starting charge. To obviate this the present invention contemplates the employment of a suitable cut-out for interrupting the sparking circuit preliminary to the introduction of the starting charge to the cylinders. For this purpose a forked lever 76 is pivoted to a supporting bracket 77 carried by the motor frame, the lever 76 and the bracket 77 being electrically connected to said frame. The lever 76 is provided with a contact lug 78 which co-operates with a contact finger 79 to which one terminal 80 of the electrical circuit is connected. Obviously, the contact finger 79 is insulated from the supporting bracket 77, so that when the lug 76 is freed from engagement with the finger 79 the electrical circuit is opened at this point. On the other hand, as soon as the lug 76 is moved into engagement with the finger 79 the circuit is closed and upon the proper operation of the timer a spark is produced in the motor. One end of the forked lever 76 is arranged in juxtaposition to the crank 17, and is adapted to contact with the latter, the other end of said lever 76 being arranged in proximity to the end of the rod 72 opposite to that with which the hand lever 30 contacts, so that when said rod 72 is oper-

ated by the hand lever 30 said rod contacts with the forked lever 76 and the lug 78 thereof is brought into engagement with the finger 79. By reason of the construction which has just been described it will be understood that on the movement of the crank 17 in a rearward direction or toward the seat of the operator of the machine, said crank actuates the forked lever 76 to open the igniting circuit at the finger 79 and the contact lug 78. On this movement the pump 14 is filling with the explosive mixture, and none of the latter has been discharged into the cylinders of the motor. Therefore, with the igniting circuit opened in the manner described on the forward movement of the crank 17, and the resultant forward movement of the pump piston, the starting charge is injected into the cylinders without liability of ignition.

In the operation of the herein-described starting apparatus, it is assumed that the pistons of the several cylinders of the motor stop at a point substantially midway between the ends of their strokes, which is generally the case when automobile explosive motors come to rest. In such position the pistons of two of the cylinders are ready to start upwardly, while the other two will move downwardly upon the starting of the motor. As illustrated in Fig. 3, the piston of cylinder 1 is about to move upwardly on the exhaust stroke, the exhaust valve being opened; the piston of cylinder 2 is moving downwardly on the power stroke. The piston of cylinder 3 is likewise moving downward on the suction stroke, the inlet valve being open, while the piston of cylinder 4 is moving upwardly on the compression stroke. In cylinders 2 and 4 both of the valves are closed, and it is assumed that the pistons come to rest on the strokes referred to but at the midway position between the ends of their strokes. This being the case, and it is desired to start the motor, the operator of the machine while remaining in his seat, grasps the hand lever 30 and gives it a lateral thrust to remove the same from the notch 32. By pulling on the lever 30 in a rearward direction, the piston of the pump 14 is drawn rearwardly, thereby creating a suction within the pump and under the influence of this suction a charge of the combustible mixture is drawn through the pipe 15 from the carburetor 12 into the pump, and is held therein by the check valve 16. As previously described, this rearward movement of the pump piston, and the corresponding movement of the crank 17, opens the ignition circuit at the contacts 76 and 79. Forward pressure is now applied to the hand lever 30, and the piston of the pump 14 responds with a forward movement, the explosive charge being thereby expelled from the

pump 14 through the check valve 20 and pipe 19 into the manifold 21 and is distributed by the latter through the feed pipes 22 to the respective auxiliary valves 23. Because of the fact that the exhaust valve 7 of cylinder 1 and the inlet valve of cylinder 3 are open at their respective rods 36 and 37, being raised by the cams 38 and 39, the locking lugs 50 of these particular 5 valve rods are in such position as to contact with the shoulders 49 of the cam sleeves 44 associated with these particular cylinders. Hence since the cam 53 rotates with the shaft 29, when the latter is actuated by the 10 hand lever 30, the cam sleeves 44 of cylinders 1 and 3 are locked against forward movement. This results in the auxiliary valves 23 of these particular cylinders remaining closed, so that the starting charge 15 is unable to gain admission to the cylinders 1 and 3. However, the inlet and exhaust valves of cylinders 2 and 4 remain closed, by reason of which fact the locking lugs 50 carried by their respective rods 36 and 37 20 are not in the path of movement of the lugs 49 of the cam sleeve 44 of cylinders 2 and 4; so that on the forward movement of the rods 48 said cam sleeves move therewith, and the cam lugs 48 of these particular 25 sleeves raise the auxiliary valve rods 25 thereby opening the auxiliary valves 23 of cylinders 2 and 4. These cylinders, therefore, receive the starting charge. If a single stroke of the handle 30 is inadequate to 30 provide the proper volume of the starting charge, it will be understood that a sufficient number of strokes is given for the injection of this required volume. This condition being satisfied, the lever 30 is moved 35 into the notch 35 thereby being brought into contact with the end of rod 72, and pushing the latter toward and into contact with the forked lever 76. As this movement continues the lug 78 is swung into engagement with the contact finger 79 closing the ignition circuit at this point, as previously described. It will be understood that with this movement of the rod 72 the bell-crank lever 71 is also swung upon its 40 fulcrum, thereby projecting the rod 69 in a forward direction, resulting in the movement of the contacts 65 into the path of movement of the contact finger 57. If the contact finger rests between the contacts 61, 45 the circuit is closed by the contacts 65 bridging the space in which the finger 57 is positioned, and a spark is created in one of the cylinders into which the starting charge has been injected. 50 Inasmuch as the piston of cylinder 2 is on its power stroke, the explosion of the starting charge occurs in this cylinder, thereby forcing the piston thereof outwardly. The piston of cylinder 4 being on its compression 55 stroke, the starting charge therein is com-

pressed as such piston rises, and at the proper time this charge is also fired. The motor is now in full operation and the combustible mixture is being drawn through the carburetor 12 and fed to the respective cylinders under normal conditions and ignition likewise follows in accordance with the normal operation of the motor. Immediately upon pressure being released from the hand lever 30, the same is returned to 70 the notch 32, and the spring 54 forces the rod 48 in a rearward direction, positioning the cam sleeves 44 also in their normal positions, wherein the cam lugs 48 thereof are removed from beneath the lower ends of the auxiliary valve rods 25, and auxiliary valves 23 become seated, and remain so until the hand lever 30 is operated again in the manner described.

While the invention is primarily designed for starting the motors of automobiles, it is to be understood that the same is capable of use with explosive motors generally, so that the invention is not limited to automobile use.

Having thus described the invention, what is claimed as new, and desired to be secured by Letters Patent, is:

1. In starting apparatus for explosive motors, the combination with a motor, of means for introducing a starting charge thereto, an auxiliary valve for controlling introduction of the starting charge to the motor, a cam device for actuating said auxiliary valve, means for actuating said cam device, and means for controlling the operation of said actuating means in accordance with the positions of the inlet and exhaust valves of the motor.

2. In starting apparatus for explosive motors, the combination with a motor, of means for introducing a starting charge thereto, an auxiliary valve for controlling introduction of the starting charge to the motor, a cam device for actuating said auxiliary valve, means for actuating said cam device, and means associated with the inlet and exhaust valves of the motor and cooperating with said cam device, whereby to control the operation of the cam device in accordance with the positions of the inlet and exhaust valves.

3. In starting apparatus for explosive motors, the combination with a motor, of means for introducing a starting charge thereto, an auxiliary valve for controlling introduction of the starting charge to the motor, a cam sleeve for actuating said auxiliary valve, an operating rod with which said cam sleeve is associated, and a yieldable connection between said cam sleeve and said rod.

4. In starting apparatus for explosive motors, the combination with a motor, of means for introducing a starting charge thereto, an auxiliary valve for controlling introduction

of said starting charge to the motor, a cam sleeve for actuating said auxiliary valve, an operating rod upon which said cam sleeve is mounted, a yieldable connection between 5 said cam sleeve and said rod, and locking devices associated with the inlet and exhaust valves of the motor and co-operating with said cam sleeve for controlling operation of the latter in accordance with the positions of the inlet and exhaust valves.

5. In starting apparatus for explosive motors, the combination with a motor, of a pump for introducing a starting charge thereto, a hand-operated device for actuating 15 said pump, means for controlling introduction of the starting charge to the motor, means controlled by said hand-operated device for actuating said controlling means in synchronism with the delivery of the starting charge from the pump, and means also controlled by said hand-operated device for firing said charge.

6. In starting apparatus for explosive motors, the combination with a motor, of a 25 pump for introducing a starting charge thereto, a hand operated device for actuating said pump, an auxiliary valve for controlling introduction of the starting charge to the motor, means actuated by said hand operated device for operating said auxiliary valve, and means also controlled by said hand-operated device for firing the starting charge.

7. In starting apparatus for explosive motors, the combination with a motor, of a 35 pump for introducing a starting charge thereto, a hand-operated device for actuating said pump, means for controlling introduction of the starting charge to the motor, means controlled by said hand-operated device for actuating said auxiliary valve, normally inactive igniting means associated with the timer of the motor, and means controlled by said hand-operated device for 40 rendering said igniting means active to explode the starting charge.

8. In starting apparatus for explosive motors, the combination with a motor, of a 50 pump for introducing a starting charge thereto, a hand-operated device for actuating said pump, an auxiliary valve for controlling introduction of the starting charge to the motor, an operating rod for said auxiliary valve, a cam device actuated by 55 said hand-operated device to open the auxiliary valve, and means working in opposition to said cam device for closing the auxiliary valve.

9. In starting apparatus for explosive motors, the combination with a motor, of a 60 pump for introducing a starting charge thereto, a hand-operated device for actuating said pump, an auxiliary valve for controlling introduction of the starting charge

to the motor, an operating rod for actuating 65 the auxiliary valve, a cam actuated by the hand-operated device for opening the auxiliary valve, and a spring associated with said operating rod and acting upon the latter in opposition to the action of said cam, 70 whereby to close the auxiliary valve.

10. In starting apparatus for explosive motors, the combination with a motor, of a pump for introducing a starting charge thereto, a shaft for actuating said pump, a 75 hand lever associated with said shaft, means actuated by said shaft for controlling introduction of the starting charge to the motor, an igniting device for firing the starting charge, a slidably mounted rod arranged in juxtaposition to said hand lever, whereby the latter is adapted to fire the charge, and connections between said rod and said igniting device for firing the charge upon operation of said hand lever.

11. In starting apparatus for explosive motors, the combination with a motor, of a pump for introducing a starting charge thereto, means for controlling introduction of the starting charge to the motor, a shaft 90 for actuating said pump, a hand lever associated with said shaft and yieldingly mounted for transverse movement, connections between said shaft and the means for controlling the introduction of the charge to the 95 motor, whereby to actuate said controlling means, an igniting device for firing the starting charge, a slidably mounted rod arranged in juxtaposition to said hand-lever, and connections between said rod and said 100 igniting device, whereby the charge is fired upon transverse manipulation of the hand lever for the actuation of said slidably mounted rod.

12. In a starting apparatus for explosive 105 motors, the combination with a motor and timer therefor, of means for introducing a starting charge to the motor, said timer having a series of contact members for the normal operation of the motor, a second series 110 of contact members adjacent those first mentioned, a contacting device successively engaging the contacts of the first series, and means for throwing the second series of contacts at times into position for engagement by the said device.

13. In starting apparatus for explosive 115 motors, the combination with a motor, of means for introducing a starting charge thereto, means for controlling introduction 120 of the starting charge to the motor, a yieldingly mounted igniting device associated with the timer of the motor, and manually controlled means for moving said igniting device into operative relation with the contact finger of the timer for exploding the 125 starting charge.

14. In starting apparatus for explosive

motors, the combination with a motor, of means for introducing a starting charge thereto, an igniting device yieldingly mounted in relation to the timer of the motor, a hand-operated device, and connections between said hand-operated device and the yieldingly mounted igniting device for moving the latter into operative relation to the

contact finger of the timer, whereby to explode the starting charge.

In testimony whereof I affix my signature in the presence of two witnesses.

FRED N. LIVINGSTON.
